UNITED STATES PATENT OFFICE.

EDWARD C. ABRAHAM, OF ALAMEDA, CALIFORNIA.

WINDOW VENTILATOR.

Application filed February 27, 1922. Serial No. 539,654.

To all whom it may concern:

Be it known that I, EDWARD C. ABRAHAM, a citizen of the United States, residing at Alameda, in the county of Alameda and 5 State of California, have invented new and useful Improvements in Window Ventilators, of which the following is a specification.

This invention relates to window ventilators and more particularly to that form of ventilator adapted to be positioned in the lower rail of a window sash, although not necessarily restricted to this position, as the same may be readily applied to the upper 15 sash, and also to doors, cars and the like.

Objects of my invention are to provide a ventilator of the character described so constructed as to permit a room to be readily ventilated without opening the window; to 20 provide improved means for controlling the influx of air into the room; to provide means associated with and actuated by control mechanism, the said means being in the form of receptacles adapted to hold medicated 25 material so that the influx of the air particularly into a sick room will be pure and extremely sanitary.

A further object of this invention is to provide a device of the character described, 30 which is simple in construction, economical to manufacture, and which can be readily inserted in the sash of a window without materially altering the construction of the same.

Other objects and advantages will be apparent during the course of the following description.

In the accompanying drawings forming a part of this specification and in which like numerals are employed to designate like 40 parts throughout the same,

Fig. 1 is a front elevation of the lower end of a window sash having my improved ventilator applied thereto,

Fig. 2 is a transverse sectional view taken 45 on the line 2—2 of Fig. 1,

Fig. 3 is a horizontal view taken on the line 3—3 of Fig. 2,

Fig. 4 is a detail plan view showing the means for holding in position the pivoted 50 door of the ventilator,

Fig. 5 is a rear elevation of the ventilator,

Fig. 6 is a modified type of ventilator, and

Fig. 7 is another type of ventilator that 55 may be employed.

In the accompanying drawings wherein

for the purpose of illustration is shown a preferred embodiment of my invention, the reference character "A" designates an ordinary window sash, the lower end rail of 60 which is provided with a longitudinal slot or opening 8, which slot extends substantially the entire width of the lower rail and is adapted to receive therein the ventilating device herewith designated as a whole 65 by the numeral 9.

The ventilating device embodies in its construction a rectangular casing including a top wall 10, a bottom wall 11, and side walls 12. This casing is adapted to fit snugly 70 in the space of the bottom rail that is provided by the opening 8, and in order that the description of the position of the casing with relation to the sash may be readily understood, the part of the casing that extends 75 within the room, as shown in Fig. 1, will be hereinafter referred to as the front of the ventilating device, while the portion that is positioned adjacent the outside of the sash, as shown to advantage in Fig. 5, will be referred to as the rear of the ventilating device. The respective walls of the casing terminate 80 at the front thereof in flanges 13, which flanges permit the casing to be secured to the bottom rail "A," and preferably detachably 85 secured, by fastening elements 14. Adjacent the rear of the casing a screen 15 is suitably retained by rear flanges 15' of the casing. The purpose of this screen is to prevent the entrance of insects or bulky foreign 90 matter into the said casing.

As shown to advantage in Fig. 5 it will be observed that the flanges 15' are cut away in order to provide means for the exit of rain water, that may enter the ventilating 95 device through the screen and accumulate therein.

A door 16 is pivotally secured to the side walls 12 of the casing, and the points of pivotal contact are preferably off center, as 100 disclosed to advantage in Fig. 2. This door has mounted adjacent its upper extremity, on the outside thereof, a handle 17, suitably curved to afford a hand hold not only for conveniently actuating the door when it 105 is desired to open or close the ventilating device, but also to present a means for readily raising the window sash when occasion may demand.

The numeral 18 designates a pair of 110 curved extremities, preferably formed integral with the door and positioned adjacent

the lower extremity of the same, but disposed on the inside thereof in contra-distinction to the curved handle 17. The purpose of these extensions will be hereinafter fully explained:

As shown to advantage in Figures 2 and 4, the top wall 10 has slots 19 formed therein adjacent the front of the casing, and the portion of the wall between the slots is longitudinally grooved or inwardly bent as at 20. The purpose of this construction is to have the inwardly bent portion 20 contact with the top of the door 16 when it is moved from the dotted line position to the full line position as shown in Fig. 2. By employing the slots 19 the portion disposed between the same will, due to its inherent spring nature, firmly engage the top of the said door, and prevent its accidental displacement from its closed position.

The numerals 21 and 22 designate receptacles which can either be made integral with the side walls 12, or can be positioned adjacent thereto. These receptacles are provided with hinged doors 23 provided with extensions 24. In each of these receptacles, I propose to insert a quantity of medicated material such as absorbent cotton on which is sprinkled carbolic acid or some suitable sanitary medicinal preparation. It will be obvious from this construction, that when the door of the ventilating device is opened, as shown in dotted line position in Fig. 2, that the extensions 18 will contact with the doors 23 and the receptacles will accordingly be opened. Thus the influx of fresh air will mix with the medicated atmosphere within the ventilating device and carry pure air into the room. The use of these receptacles in conjunction with the ventilating device is preferably for hospital rooms, although it is to be understood that the ventilating device can be readily constructed without the use of these receptacles. In order to limit the upward movement of the hinged doors 23, stops 25 provided on the walls 12 are positioned directly above the said doors.

While I have shown a rectangular casing disposed within the bottom rail "A" of the window sash nevertheless, it is to be understood that modified forms of devices such as those of a round or oval shape as shown in Figs. 6 and 7, can likewise be employed. These said modified forms can readily accommodate the various parts of the device as before described, except that the door 16 will be made to conform to the shape of the device used.

It is to be understood that the form of

my invention, herewith shown and described is to be taken as a preferred example of the same, and that various changes in the shape, size and arrangement of parts may be resorted to without departing from the spirit of the invention or the scope of the subjoined claims.

Having thus described my invention, I claim:

1. A device of the character described, comprising a casing, having ventilating openings therein, a screen in said casing, medicine holding receptacles connected to said casing, and having hinged lids therein, and a door pivotally mounted in said casing and adapted to contact with the lids of the said receptacles for the purpose of raising said lids when said door is moved to an open position, and locking means in the top of said casing for retaining said door in a closed position.

2. In a window ventilator, a casing having a ventilating opening therein and terminating in front flanges adapted to be detachably secured to the rail of a window sash and continuing into rear flanges having cut away portions provided therein, a screen secured in the rear flanges of said casing, disinfectant holding receptacles connected to said casing and provided with hinged lids thereon, a door eccentrically pivoted in said casing having a handle on the outside thereof and extensions on the inside thereof, adapted to contact with the lids of the receptacle upon the opening of said door, and locking means formed in said casing for retaining said door in a fixed position upon the closing of said door.

3. In a window ventilator, a casing having a ventilating opening therein and terminating in front flanges adapted to be detachably secured to the rail of a window sash and continuing into rear flanges having cut away portions provided therein, a screen secured in the rear flanges of said casing, disinfectant holding receptacles connected to said casing and provided with hinged lids thereon, a door eccentrically pivoted in said casing having a handle on the outside thereof and extensions on the inside thereof, adapted to contact with the lids of the receptacle upon the opening of said door, stops disposed above the receptacle for limiting the upward movement of the lids thereof, and locking means formed in said casing for retaining said door in a fixed position upon the closing of said door.

In testimony whereof I affix my signature.

EDWARD C. ABRAHAM.
